(57) **CLAIM**

The ornamental design of a packaging with surface ornamentation, as shown and described.

DESCRIPTION

FIG. 1 is a front view of a packaging with surface ornamentation incorporating the design;

FIG. 2 is a front view of a second embodiment thereof;

FIG. 3 is a front view of a third embodiment thereof; and,

FIG. 4 is a front view of a fourth embodiment thereof.

The broken lines in the drawings illustrate a packaging element and form no part of the claimed design.

The claim is directed to a surface ornamentation on a flat surface.
